US00D970996S

(12) **United States Design Patent** (10) **Patent No.:** **US D970,996 S**
Lin (45) **Date of Patent:** **** Nov. 29, 2022**

(54) **WIRE STRIPPER**

(71) Applicant: **Hanlong Industrial Co., Ltd.**, New
 Taipei (TW)

(72) Inventor: **Pai-Wei Lin**, New Taipei (TW)

(73) Assignee: **Hanlong Industrial Co., Ltd.**, New
 Taipei (TW)

(**) Term: **15 Years**

(21) Appl. No.: **29/757,086**

(22) Filed: **Nov. 3, 2020**

(51) LOC (13) Cl. **08-05**

(52) U.S. Cl.

USPC **D8/52**

(57) **CLAIM**

The ornamental design for a wire stripper, as shown and described.

DESCRIPTION

FIG. 1 is a perspective view of a wire stripper, showing my new design;

FIG. 2 is a front view thereof;

FIG. 3 is a rear view thereof;

FIG. 4 is a left view thereof;

FIG. 5 is a right view thereof;

FIG. 6 is a top view thereof; and,

FIG. 7 is a bottom view thereof.

The broken lines depict portions of the wire stripper that form no part of the claimed design.

1 Claim, 6 Drawing Sheets
